ATTORNEY,

UNITED STATES PATENT OFFICE.

GEORGE HENRY CHAPPELL, WILLIAM BROWN, AND JOHN BROWN, OF BROWNTON, MINNESOTA.

HEAD-PROTECTOR.

SPECIFICATION forming part of Letters Patent No. 396,141, dated January 15, 1889.

Application filed May 8, 1888. Serial No. 273,174. (No model.)

To all whom it may concern:

Be it known that we, GEORGE HENRY CHAPPELL, WILLIAM BROWN, and JOHN BROWN, all of Browntown, in the county of McLeod and State of Minnesota, have invented a new and Improved Head-Protector, of which the following is a full, clear, and exact description.

Reference is to be had to the accompanying drawings, forming a part of this specification, in which similar letters of reference indicate corresponding parts in both views.

Figure 1 illustrates our invention applied for use, the protector being broken away to show the construction; and Fig. 2 is a detailed perspective view of the lower ring and one of the hinged arms or ribs.

This invention relates to a device to be worn upon the shoulders and around and over the head to protect the face and neck of the wearer from driving snow-storms and inclement weather generally; and the object of the invention is such construction of the protector that it is adapted to be attached to and supported entirely from the shoulders of the wearer.

Another object is to so construct and combine the parts of the protector that when the top covering is removed the arms or ribs to which the outer web is attached may be turned down over the breast, shoulders, and back of the wearer.

The invention consists of the construction, arrangement, and combination of parts, all as hereinafter described and claimed.

A represents a ring of sheet metal folded at the edges to form the ways *a a*. One end of the ring is provided with a buckle, *b*, and the other with a strap, *b'*, for securing the ring around the head of the wearer, as shown in Fig. 1. At each side the said ring *A* is provided with plates *c c*, formed with slots *c' c'*, and to these plates are secured the curved plates *d d*, provided with the curved shoulder-

plates *f*, adapted to be secured by straps *f'* to the shoulders of the wearer. The slots *c'* 45 permit the plates *d* to be adjusted, and in the lower or outer ends of these plates are formed the slots *c²*, by which the curved shoulder-plates *f* may be adjusted.

In the ways *a a* of the ring *A* are placed 50 numerous sliding blocks, *g*, to which are hinged the arms or ribs *h*. To these arms is secured the encircling web *B*, and also the top covering, *C*, each arm being provided with a button, *i*, or other fastening device, for receiving 55 and holding the said web and covering, as shown clearly in Fig. 1.

One edge of the web *B* is formed with the button-holes *j*, while the opposite edge is provided with corresponding buttons, so that the 60 edges may be secured together, and the arms or ribs *h* nearest the ends of the rings *A* are each provided with a draw-string, *k*, by which the edges of the web may be drawn together or opened. When the top covering, *C*, is removed, the arms or ribs *h* and the web *B* may be turned down over the breast, shoulders, and back of the wearer out of the way.

Having thus described our invention, we claim as new and desire to secure by Letters 70 Patent—

1. The head-protector herein shown and described, the same consisting of the ring *A*, sliding ribs or arms *h*, connected thereto, supports *c d*, shoulder-pieces *f*, and web and covering *B C*, substantially as described. 75

2. In a head-protector, the ring *A*, formed with ways *a*, in combination with the sliding plates *g* and the arms or ribs *h*, hinged thereto, substantially as described.

GEORGE HENRY CHAPPELL.
WILLIAM BROWN.
JOHN BROWN.
